PAPER BREAKING GUN

Otto A. Langos, Chicago, Ill., assignor to Alfred F. Langos, Otto E. Langos, Harold L. Langos, Louis A. Langos, and Matilda R. Langos, partners, doing business as Langson Manufacturing Co., Chicago, Ill.

Application May 10, 1941, Serial No. 392,854

2 Claims. (Cl. 46—195)

This invention relates to toy air guns producing the sound of a gun shot by bursting paper with compressed air, and more in particular to a guide and support for a roll of paper in combination with a gun of a type such as is disclosed in my Patent No. 2,083,535. This application is a continuation in part of my copending application Serial No. 123,661, filed February 2, 1937 and issued as Patent 2,265,606.

It is an object of my invention to provide in a pleasing appearing and efficiently operating combination a paper breaker toy gun and an improved holder for supporting rolled paper to feed through the gun.

Another object is to provide a paper holder for such a gun, which holder will retain a paper roll against unrolling to an undesirable amount or becoming loosened and falling to one side or the other out of the normal rolled position at right angles to the rotating axis of the roll during all times of handling of the gun.

A further object of my invention is to provide a simplified paper holder wherein a portion thereof cooperates in the assembly of the compression chamber of the toy gun in forming an outlet for said chamber at one end thereof.

A still further object is to provide a holder for rolled paper for a feeding movement in a continuous strip, with said holder including a housing conforming substantially to the shape of the paper roll and having retaining means rotatably mounted thereon for retaining the roll therein.

Yet another object of my invention is to provide a simplified paper holder wherein portions thereof cooperate in the assembly of the means for sealing a portion of the paper across the outlet in the compression chamber of the toy gun.

Further objects, features and advantages of my invention will be apparent from the following description when taken in connection with the accompanying drawing, in which:

Fig. 1 is a side elevation of the complete gun and paper holder assembly in its preferred embodiment with certain portions broken away for clarity;

Fig. 2 is a fragmentary sectional view as seen along the line 2—2 in Fig. 1;

Fig. 3 is a fragmentary front elevation of the structure of Fig. 1, taken along the line 3—3 and showing parts thereof in section;

Fig. 4 is a fragmentary side elevation of a modified embodiment of the paper holder in combination with the gun of Fig. 1;

Fig. 5 is a fragmentary top plan view of the paper holder structure shown in Fig. 4;

Fig. 6 is a fragmentary sectional view as seen on line 6—6 in Fig. 5;

Fig. 7 is a fragmentary front elevation of a further modified embodiment of the paper holder in combination with the gun of Fig. 1; and

Fig. 8 is a fragmentary side elevation of the complete paper holder of Fig. 7, with portions thereof shown in section.

In practicing my invention, I provide a paper bursting toy gun, having a compression chamber in the barrel thereof, and means for sealing a paper strip across an outlet from the compression chamber to burst the paper with compressed air. The paper is fed in a continuous strip from a roll 10 carried in a housing on the gun barrel, with a portion of the housing cooperating to form the outlet at the end of the compression chamber of the gun. The housing is provided in a substantially cylindrical casing to correspond with the 15 form of the paper roll and has a paper inserting opening and paper retaining means rotatably supported thereon.

To facilitate reference to my prior patent on that structure which is common to that patent 20 and to the present application, the same reference characters are applied to all common structure.

Fig. 1 illustrates a toy gun of a type such as is disclosed in my prior patent referred to above, 30 having a handle 11 and a trigger member 63 adapted to be grasped by the user, with the trigger operating through the spring and release mechanism described in my patent, and including a piston 26 (Fig. 2) and compression spring 35 34 carried thereon. A two-piece gun barrel 12 carries a cylinder 16 in the front end thereof, the gun barrel being formed with portions 18 which are adapted to be bent into cooperating 40 apertures 10 in the cylinder walls for locking engagement with the cylinder 16. The piston and spring mechanism are entirely enclosed within the gun, the piston having a metal washer 20 on the end thereof engaging the inside wall of the cylinder 16 to compress the air therein as the 45 piston is moved forwardly under spring pressure and after the release thereof at the end of the cocking action by the trigger member 63. The inside of the cylinder is supplied with white lead or the like, which has high lubricating as well as 50 air sealing qualities, so that the metal washer 20 operates both efficiently and easily during the compression stroke of the piston 26.

As has been explained in my above-noted patent and as will be apparent from Figs. 1 and 2, 55 which illustrate the gun structure for all of the

embodiments of the present invention, a strip of paper 47 is sealed across the outlet from the cylinder 16 to be burst by the discharge of air through such outlet. The strip of paper 47 is fed from a roll of paper 51 by paper sealing and feeding mechanism including a metal slide designated generally as 45 and having a front end or sealing portion 48 and a movably carried feeding jaw 56 on the top of the slide having teeth at its end 57 engaging the paper 47 and extending to a feeding plate 39 intergral with the mounting or plate portion 37 for the roll carrying housing 76 as will be hereinafter described. The plate portion 37 has an aperture therein surrounded by an upset flange 38 (Fig. 2) which is pressed over the inwardly flanged end 36 of the cylinder 16 to rigidly mount the paper carrying housing 76 on the cylinder and barrel assembly of the gun. A rubber grommet 41 is adapted to be retained at the cylinder outlet by a cooperating assembly with the flange 38, the rubber grommet providing a cushion against which the sealing portion 48 presses the paper 47 to provide an air tight seal over the compression chamber outlet to make possible the bursting of the paper with a loud noise.

My air gun is a repeating device and will fire or burst the paper as rapidly as the operator may compress the trigger member 63 with his fingers to cock the gun and permit the release of the piston 26.

The preferred embodiment of the combination is illustrated in Figs. 1 to 3, inclusive, and shows the housing 76 for carrying the roll of paper 51 supported below the gun. The housing includes a substantially cylindrical casing portion 35 having one end thereof closed by an integral side wall 13. The mounting portion 37, casing portion 35, and side wall 13 are formed from a single piece of sheet metal. The opposite end of the casing 35 is adapted to be closed by a slidable door 14 which is rotatably supported on axis means 59 located intermediate the mounting portion 37 and the casing 35. The casing 35 at a point substantially opposite from the pivot means 59 is formed with an axially projecting lip 17 which releasably engages a recess or notch 60 in the door 14, to hold the door 14 in a closed position. With the door 14 opened, therefore, the paper roll is readily inserted within the casing 35, the roll 51 being retained within the casing when the door is in its locked position. The peripheral end portion 15 of the casing 35 is spaced from the lower end of the mounting portion 37 to form an aperture or opening through which the paper from the roll 51 is fed into the paper feeding mechanism above described.

The mounting portion 37 on opposite sides of the aperture 30 therein is formed with vertically extending flanges 61 positioned on each side of the gun barrel 12 and bent inwardly of the gun. Each flange 61 substantially intermediate the ends thereof, has a cut-out portion 19 or guideway, with each guideway 19 being adapted to slidably support a corresponding one of the pair of guide arms 21 on the metal slide 45. As is clearly apparent from Figs. 1, 2 and 3 the guide arms 21 are integrally formed at one end with the sealing portion 48, while their opposite ends are operatively connected as by a pin 22 with the spring and release mechanism which is fully explained in my prior patent. On operation of the gun, therefore, the sealing portion 48 is moved to the compression chamber outlet by the slidable support of the arms 21 in the guideways 19. The mounting portion 37, therefore, not only serves to

rigidly mount the paper carrying housing 76 on the gun, but is formed to cooperate in the assembly of the compression chamber within the cylinder 16 and of the means for sealing a portion of the paper 47 across the compression chamber outlet.

A further embodiment of the combination structure is illustrated in Figs. 4-6, inclusive, and includes a housing 23 supported above the gun and having a casing 24 which extends downwardly to the mounting portion 37 and upwardly in cylindrical form to a point 25 on the housing 23 which is located substantially opposite the mounting portion 37, as is clearly shown in Fig. 6. A slidable cover 62 is rotatably supported at apertures 27 in the casing side walls 28 bent to right angles with the casing 24 and formed integral therewith through a connecting portion indicated in Figs. 5 and 6 as 64. The cover 62 is shown in full lines in closed position (Fig. 4) to retain the roll of paper 51 therein, while the dotted lines in Fig. 4 indicate the cover in open position. A projection 29 on the casing 24 serves to releasably lock the cover 62 in closed position, while the opening of the cover is facilitated by a bevelled portion 31 (Figs. 5 and 6) which helps to guide depression 32 over the projection 29 to readily open the cover. A guideway 33 centrally of the cover and guideways 65 adjacent the edges fit over the projection 29 and beads 66 respectively, as the cover is moved to an open position. When the cover is in closed position, a slot formed by the lower edge 40 of the cover and the bend 38 intermediate the casing 24 and mounting portion 37 forms a guiding opening to guide the paper from the roll 51 into the feeding mechanism of the gun.

Yet another embodiment of the combination structure is illustrated in Figs. 7 and 8 in which the housing 67 is supported above the gun and includes a semi-cylindrical casing 42 and integral side walls 43 and 44 bent to right angles with the casing 42 and connected thereto by short connecting portions as indicated at 46 in Fig. 8. The casing 42 with its integral side walls 43 and 44 extends downwardly to the mounting plate portion 37, the casing 42 and mounting portion 37 being stamped out from a single piece of metal. As previously described, the mounting portion 37 is provided with a flanged aperture for securing the mounting portion, and in fact the entire housing 67 to the cylinder 16 in the gun proper. The casing 42 extends from the bend 38 to terminate peripherally in a curved integral lip 68 which is formed so as to engage the transverse or handle portion 49 of the roll retaining member 50 in a substantially spring catch action.

The retaining member 50 is formed from wire substantially of the size indicated in Fig. 7 and includes a transverse axis portion 52 and a radial arm 53 extending to the handle portion 49. The radial arm portion 53 is of a length slightly greater than the radius of the circular wall 44. The member 50 is rotatably mounted in correspondingly positioned apertures 54 and 55 in the side walls 43 and 44, respectively, of the housing. In the original mounting of this member the normal sized outer end of the portion 52 is inserted through aperture 55 and then flattened out in any desired manner to the configuration at 58 shown particularly in Fig. 8. This flattened end 58 may be inserted through the corresponding aperture 55 in the opposite side wall of the housing. To insert the paper roll 51 in the housing, the handle portion 49 is snapped out of the lip 68 and brought forwardly until the flattened end 58 may be withdrawn through the slot 54, after which the paper

roll 51 is inserted in the walled housing, and the retaining member 50 reinserted through the slot 54 and moved to the position shown in Fig. 8. In a commercial embodiment of the structure it has been found that the paper roll is amply protected against damage, feeds satisfactorily out of the housing, and is retained by the walls 43 and 44 from falling to one side or the other.

In utilizing only a two-piece assembly for the complete housing for the paper roll, and then employing the mounting portion of that housing to cooperate with the barrel and cylinder structure of the gun to complete the gun assembly in providing an outlet for the cylinder and a slidable support for the paper sealing means at the cylinder outlet, a minimum of material is used without in any way sacrificing ruggedness, simplicity, and the artistic merit of the gun combination.

Although the invention has been described in its preferred embodiments, it is to be understood that it is not to be so limited since modifications and alterations therein can be made which are within the full intended scope of the invention as defined by the appended claims.

I claim:

1. In an air gun including a cylinder having an inwardly extending flange at one end to provide an opening as an outlet therefrom, and employing burstable firing material, the improvement which comprises means for supporting said firing material to one side of said outlet, and including a mounting portion extending across said outlet and having an aperture therein corresponding to said outlet, said mounting portion having a flange around said aperture and upset to engage the flange forming the opening in the cylinder to mount said firing material supporting means on

said gun, a pair of guideways on said mounting portion on opposite sides of said gun, means feeding said burstable material across said outlet, and means movable substantially axially of said outlet for sealing a portion of said burstable material across said outlet, said sealing means having a pair of guide arms integral therewith, with each guide arm being slidably supported in a corresponding one of said guideways.

2. In an air gun including a cylinder having an inwardly extending flange at one end to provide an opening as an outlet therefrom, with said gun employing paper in rolled form provided as firing material for said gun and adapted to be fed to said cylinder outlet, the means for supporting said paper roll to one side of said outlet including a substantially cylindrical paper holder portion and a mounting portion extending across said outlet, with said mounting portion having an aperture therein corresponding to said outlet, and a flange around said aperture in locking engagement with the flange forming the outlet in said cylinder to mount said paper supporting means on the gun, said paper holder portion having an opening for inserting the paper roll therein, paper retaining means rotatably supported on said paper holder portion and rotatable to a position to retain said paper roll therein, side flanges on said mounting portion on opposite sides of said gun and extending inwardly thereof, with each of said side flanges having a guideway formed therein, and means for sealing a portion of said paper roll across said outlet including guiding portions, with each of said guiding portions being slidably supported in a corresponding one of said guideways.

OTTO A. LANGOS.
